UNITED STATES PATENT OFFICE.

MICHAEL ALLEN, OF SCHENECTADY, NEW YORK.

IMPROVEMENT IN HYDRANTS.

Specification forming part of Letters Patent No. 149,628, dated April 14, 1874; application filed April 19, 1873.

To all whom it may concern:

Be it known that I, MICHAEL ALLEN, of Schenectady, in the county of Schenectady and State of New York, have invented a new and Improved Hydrant, of which the following is a specification:

The invention will first be fully described, and then pointed out in the claim.

Figure 1 is a sectional elevation of my improved hydrant. Fig. 2 is a sectional elevation of the lower portion on a larger scale. Fig. 3 is a horizontal section on the line *xx* of Fig. 2, and Fig. 4 is a horizontal section on the line *zz*.

Similar letters of reference indicate corresponding parts.

A represents a short vertical tube projecting from the upper side of the branch *B* of the water-main. *C* is a flange inside of this tube at its base, whereon the large central tube *D*, for conducting the water to the top of the hydrant, is seated, with a ring or gasket of elastic packing, *E*, to make a water-tight joint. The tube is pressed down firmly on this seat by the rods *F*, connected with tube *A* by the lugs *G*, and with tube *D* by lugs *H*, the latter being above the top of the ground, where the rods can be connected and screwed up readily. *J* is a cap-piece, comprising the upper portion of the hydrant above ground. It screws onto the top of *D* at *K*, and it has a skirt, *L*, extending down over the top of *I*, to protect the space inside from being filled with earth, also to hold the tube in place. *M* is the valve, which closes against a seat in the lower end of tube *D*. It has two bars, *N*, extending a short distance upward from the upper side in the guideways *O*, and joining onto the cross-head *P*, through which the screw *Q* works to open and close the valve, said screw being fitted in a bridge-tree, *R*, for a bearing, with a

collar, *S*, above and below to prevent end motion, and at the upper end it connects by a square head with the rod *T*, having a socket in which the head is fitted, as shown, and extending up through the cap *J* at the top, where a stuffing-box, *U*, is arranged for packing the rod, so as to prevent the escape of the water. A wrench or crank of any kind is used for turning the rod to work the valve-screw. The bridge-tree *R* for the valve-screw is not cast together with the tube, but made separately and fitted in between the ribs *V*, and secured by screws *W*.

For the escape of the water I have a passage, *X*, opposite one of the bars *N*, with a hole, *Y*, in the latter, which comes opposite passage *X* when the valve is closed, and opens a free passage for the water remaining in tube *D*, after the valve is shut, to escape; but when the valve is open the hole *Y* passes below passage *X*, and cuts off the escape, so that there is no unnecessary waste when the valve is open, as in some other hydrants.

To pack the joint so as to prevent leakage between the bar *N* and the bottom of the groove in which it works, I have a thimble, *a*, in the passage *X*, an elastic ring, *b*, and an adjusting-nut, *d*, by which the inner end of the thimble is pressed water-tight on the bar.

Having thus described my invention, I claim as new and desire to secure by Letters Patent—

The waste-passages, arranged as described, in combination with the thimble *a*, elastic ring *b*, and adjusting-nut *d*, for the purpose set forth.

MICHAEL ALLEN.
